No. 13,173

Aug 15, 1882

UNITED STATES PATENT OFFICE.

JAMES BOWERS, OF NEWARK, NEW JERSEY.

DESIGN FOR A CORSET.

SPECIFICATION forming part of Design No. 13,173, dated August 15, 1882.

Application filed July 8, 1882. Term of patent 7 years.

To all whom it may concern:

Be it known that I, JAMES BOWERS, a citizen of the United States, residing at Newark, in the county of Essex and State of New Jersey, have invented and produced a new and original Design for Corsets; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

The photographic representation hereto attached represents an elevation of a half-section of my newly-designed corset, which is deemed sufficient to fully illustrate the same.

The leading feature of my design consists in the combination with the ordinary flat stiffeners, *a*, or, more properly, the ribs formed thereby, of finer ribs, *b*, arranged at the ends thereof and running in approximately the same direction, said finer ribs, *b*, being arranged either in the bottom or top of the corset, or both, as indicated in the drawing.

The said finer ribs are formed as follows: The stiffeners *a*, being shorter than those usually employed, leave an unoccupied space between the ends thereof and the edges of the corset, into which space is secured the shorter bones or cords, *b*, preferably two bones or cords to each rib *a*, as shown. I prefer to arrange the ribs *a* vertically, or approximately so, the finer ribs,

b, continuing in the same direction, or nearly so, to the edge of the corset. Said finer ribs *b* being arranged in the corset-body anywhere between the busk-pockets upon the lacing or clasping edges of the corset in clusters, produce a very novel and pleasing effect.

Having thus described my design, what I claim is—

1. The design for a corset, herein shown and described, the same consisting of the short raised ribs *b* at the top or bottom edge, in connection with the approximately plain or flat-ribbed central portion of said corset.

2. The design for a corset, herein shown and described, the same consisting of the short raised ribs *b*, arranged in groups at the top or bottom edge of said corset, in connection with the flat-ribbed or smoother portion thereof.

3. The design for a corset, the same consisting in the approximately-vertical ribs *a* shorter than the body of the corset, having at either extremity thereof the shorter and narrower ribs, *b*, continuing in approximately the same direction to the edge of the corset, as herein shown and described.

In testimony that I claim the foregoing I have hereunto set my hand this 6th day of July, 1882.

JAMES BOWERS.
